UNITED STATES PATENT OFFICE

JAMES RAYMOND O'BRIEN, OF CHICAGO, ILLINOIS, ASSIGNOR, BY MESNE ASSIGNMENTS, TO JOSEPH LODA, OF DOVER, DELAWARE

ROAD MARKER

Application filed August 7, 1926. Serial No. 127,745.

This invention relates to improvements in markers particularly adapted, though not necessarily limited for use in connection with roads and other surfaces, and has for one of its objects to provide an improved marker of this character which while constructed with a block like resilient body portion, is provided with an anchor plate of a different and non-resilient material, preferably metal, upon which the block rests and to which it is secured, and to which plate anchor members or bolts are connected to depend therebelow to be embedded in the pavement for firmly securing the marker in position.

15 A further object is to provide an improved marker of this character in which the anchor or base plate preferably terminates substantially flush with one or more of the upright lateral faces of the block like body portion, thereby rendering it possible to assemble a plurality of the marker elements or blocks with their adjacent lateral faces abutting to form the desired character or object, and improved means for locking or securing together the adjacent sections or elements, whereby the object or character thus delineated may be anchored as a unit to the pavement.

To the attainment of these ends and the accomplishment of other new and useful objects as will appear, the invention consists in the features of novelty in substantially the construction, combination and arrangement of the several parts hereinafter more fully described and claimed and shown in the accompanying drawing illustrating this invention, and in which

40 Figure 1 is a top plan view of a plurality of marker elements constructed in accordance with the principles of this invention, assembled to form a character and showing the same embedded in a pavement or road bed.

45 Figure 2 is a detail perspective view of several of the elements assembled and as viewed from the bottom.

Figure 3 is a detail perspective view of one of the elements.

50 Figure 4 is a detail perspective view of an anchor element or member.

Figure 5 is an enlarged detail sectional view taken on line 5-5, Figure 1.

As shown in the drawing each of the marker elements embodies a body portion 10 of a block like formation which may be of any desired size and configuration and constructed of any suitable material, preferably rubber or composition which may be produced in any manner and the material is of such a nature that it will withstand considerable wear, but will yield to a certain extent under the pressure of a load passing upon or from the element.

Secured to the bottom of the body portion thus formed and in any desired or suitable manner is a plate or member 11, which is constructed of any suitable material preferably metal, or it may be constructed of any other suitable material different from the material from which the body is constructed in that the plate 11 will be of a greater rigidity.

The plate 11 is preferably of a size and configuration that its peripheral edges will be substantially flush with the lateral or upright edges of the body portion 10 and may be of any desired thickness suitable for the purpose.

Depending below the plate 11 are a plurality of anchor elements 12 preferably in the form of threaded bolts which pass through the plate 11 so that the heads 13 will rest upon the upper surface of the plate 11. If desired, the heads 13 may be convexed in form so as to be embedded in the adjacent face of the block like body portion 10 when the elements 10 and 11 are secured together.

If desired a portion 14 of the bolts or anchors 12 may be angular in cross section and pass through similarly shaped apertures 15 in the plate 11 so as to hold the bolts or anchors 12 against rotation with respect to the plate 11.

Any desired number of these anchor bolts 12 may be employed and they may depend for any desired distance below the plate 11.

A marker element thus formed is secured in position with respect to the pavement 16 by forming in the pavement a recess into which the element is inserted, and if desired and before the element is placed in position

a nut or collar 17 may be threaded upon the bolt 12 so as to engage the lower face of the plate 11 and thereby assist in securing the anchor bolt to the plate 11.

5 When the marker element thus constructed is placed in position the recess in the pavement is filled in with concrete or any suitable plastic material so as to hold the same in position.

10 Anchor members 18 may be provided if desired, and are adapted to be threaded upon the bolts 12 so as to project therebelow and form an additional means for assisting in anchoring the element.

15 With the present invention it will be manifest that the lateral or upright faces of each of the marker elements is substantially straight and as the edge of the plate 11 is flush with the lateral face of the body portion of the marker element, a plurality of the elements may be placed side by side so as to abut, as shown in Figure 1. This renders it possible to build up, by the use of a plurality of these marker elements, any desired character such as letters or the like and by securing the adjacent marker elements together the entire built up character may be placed in a pavement and anchored as a unit.

20 Any suitable means may be provided for binding or connecting the respective elements together. An effective and efficient means embodies a plurality of plates or members 19 provided with suitable apertures there- 25 through, and these plates or members 19 are adapted to be sleeved upon the proximate bolts or anchor members 12 of the adjacent marker sections so that the plates 19 will extend across the abutting edges of the adjacent plates 11.

25 After the marker elements have been assembled or adjacent elements arranged in proximity to each other, the respective plates 19 are placed in position. The nuts or collars 17 are then threaded upon the bolts or members 12 and cooperate with the respective heads 13 of the bolts for clamping the members 19 against the lower face of the adjacent plates 11, as shown more clearly in Figures 30 2 and 5.

35 In assembling or forming any desired character it is preferable to invert the marker elements so that the plates 19 and collars or nuts 17 may be readily placed in position.

40 The additional marker elements 18 are then attached to any desired number or all of the bolts 12, after which the assembled character may be placed in position in the pavement 16 by inserting the same into a recess formed in the pavement. The recess may then be filled with concrete or plastic material, and the marker is placed in position so that the upper face of the body portion 10 thereof will be substantially flush with the exposed surface of the pavement.

With this improved construction it will be manifest that there will be provided an extremely efficient and durable marker which will be firmly anchored by reason of the fact that the plate 11 will be of a non-resilient nature and the upper portion or body 10 of the element will be of a more or less resilient nature. The upper surface of the element will yield with the pavement and also when a heavy vehicle is passing thereupon and by reason of such resiliency the life of the element will be greatly prolonged.

70 The non-resilient plate which is firmly anchored in the pavement will prevent the element from becoming detached or displaced 75 with respect to the pavement.

80 By reason of the non-resilient nature and of the material of which the plate 11 is constructed, it will not be affected by the action of heat or cold, with the result that the element will always be firmly anchored.

85 The resilient upper portion or body of the block will yield with the pavement and will not be torn away from the adjacent faces of the wall of the opening in the pavement into 90 which the element is inserted.

95 It will also be manifest that with this improved element any form of letter or character may be built up by the use of a plurality of the elements and the elements may all be secured together so as to constitute a single unit.

100 Obviously many changes may be made in the details of construction and in the combination and arrangement of the several parts, 100 within the scope of the claims, without departing from the spirit of this invention.

What is claimed as new is:—

105 1. A road marker embodying a plurality of elements each embodying a resilient block like body portion, the upper surface being substantially flat, a non-resilient plate upon which the block rests, the lower surface of the block and said plate being secured together, the edge of the plate being substantially flush with the lateral wall of the block, an anchor member connected with the plate and depending therebelow, the proximate faces of adjacent elements abutting, and a connecting member extending across the joint between 110 adjacent elements and secured to one of the anchor members of each of the elements.

115 2. A road marker embodying a plurality of elements each embodying a resilient block like body portion, the upper surface being substantially flat, a non-resilient plate upon which the block rests, the lower surface of the block and said plate being secured together, the edge of the plate being substantially flush with the lateral wall of the block, an anchor member connected with the plate and depending therebelow, the proximate faces of adjacent elements abutting, a connecting member extending across the joint between 120 adjacent elements, and means securing the 125 exposed surface of the pavement.

connecting member against the exposed face of the said plate.

3. A road marker embodying a plurality of elements each embodying a resilient body portion, a non-resilient plate upon which the said body portion rests, the lower face of the said body portion and the plate being secured together, the edge of the plate being substantially flush with the lateral edge of the said body portion, an anchor bolt connected with and depending below the plate, said bolt being threaded, the proximate faces of adjacent elements abutting, a tie member extending across the joint between adjacent sections and engaging said bolts, and nuts on the respective bolts for securing the said tie member in position and for clamping it against the lower face of the said plate for securing the said elements together.

20 4. A road marker embodying a plurality of elements each embodying a resilient body portion, a non-resilient plate upon which the said body portion rests, the lower face of the said body portion and the plate being secured together, the edge of the plate being substantially flush with the lateral edge of the said body portion, an anchor bolt connected with and depending below the plate, said bolt being threaded, the proximate faces of adjacent elements abutting, a tie member extending across the joint between adjacent sections and engaging said bolts, nuts on the respective bolts for securing the said tie member in position and for clamping it against the lower face of the said plate for securing the said elements together, and an additional anchor element connected with the said bolt.

5. A road marker embodying a plurality of block like body portions adapted to be embedded in a pavement with their upper faces substantially flush with the surface of the pavement, an anchor member connected with and depending below each of the blocks, and a fastening member extending across the bottoms of adjacent blocks and engaging adjacent anchor members for securing the marker elements together.

6. A road marker embodying a plurality of block like body portions adapted to be embedded in a pavement with their upper faces substantially flush with the surface of the pavement, an anchor member connected with and depending below each of the blocks, a fastening member extending across the bottoms of adjacent blocks, said fastening member having apertures therethrough through which the respective anchor members pass, and means engaging the said anchors for clamping the said fastening member against the lower face of said body portion for securing the marker elements together.

7. A road marker embodying a plurality of elements each embodying a resilient block like body portion, a non-resilient plate upon which the block rests, the lower surface of

the block and said plate being secured together, the edge of the plate being substantially flush with the lateral wall of the block, an anchor member connected with the plate and depending therebelow, and a connecting member below the elements and extending from one element to the next adjacent element and secured to one of the anchor members of each of the elements.

8. A road marker embodying a plurality of elements each embodying a resilient body portion, a non-resilient plate upon which the block rests, the lower surface of the block and the said plate being secured together, the edge of the plate being substantially flush with the lateral wall of the block, an anchor member connected with the plate and depending therebelow, a connecting member below the elements and extending from one element to the next adjacent element, and means securing the connecting member against the exposed face of the said plate.

9. A road marker element embodying a resilient body portion, a plate secured to the bottom of said body, an anchor member connected with the plate and depending therebelow, all of said parts being adapted to be embedded in a pavement with the upper surface of the resilient body substantially flush with the surface of the adjacent portion of the pavement, and means engaging an anchor member of adjacent elements for tying them together, the said means being disposed below the said elements and also embedded in the pavement.

In testimony whereof I have signed my name to this specification on this 4th day of August, A. D. 1926.

J. RAYMOND O'BRIEN.
